UNITED STATES PATENT OFFICE

EDWIN W. SEEGER, OF SOUTH MILWAUKEE, WISCONSIN, ASSIGNOR, BY MESNE ASSIGNMENTS, TO CUTLER-HAMMER, INC., OF MILWAUKEE, WISCONSIN, A CORPORATION OF DELAWARE

SIGNAL SYSTEM FOR PRINTING PRESSES

Application filed December 31, 1926. Serial No. 158,295.

This invention relates to controllers for multi-unit printing presses and similar mechanisms and is particularly applicable to signal systems therefor.

5 The patent to Thomas H. Rodman and Paul W. Darlington, No. 1,616,760, dated February 8, 1927, discloses a control system for multi-unit printing presses including driving connections which are commutatable 10 to suit various drive combinations between the driving and driven units and control switches operable to effect control commutations to suit the various drive combinations.

An object of the present invention is to provide 15 a controller of the aforesaid character having improved signalling means associated therewith for indicating whether or not the driving connections are properly set for a given drive combination.

20 Another object is to provide a controller of the aforesaid character having improved signalling means associated therewith for indicating whether or not the circuit controlling switches are properly set for a given drive 25 combination.

Various other objects and advantages of the invention will hereinafter appear.

The accompanying drawings schematically and diagrammatically illustrate an embodiment 30 of the invention which will now be described, it being understood that the embodiment illustrated may be modified in certain respects without departing from the spirit and scope of the appended claims.

35 In the drawing,

Figure 1 is a schematic view of the driven units and the drives therefor;

Fig. 2 is a schematic and diagrammatic view of the driven units and driving motors 40 therefor, together with commutatable control means for the motors;

Fig. 3 is a diagrammatic view of a signalling system for the driving means illustrated in Fig. 1, and

45 Fig. 4 is a diagrammatic view of a signalling system for the commutatable control means illustrated in Fig. 2.

50 Referring to Fig. 1, the same illustrates a driven machine which may be assumed to be a printing press comprising twelve printing

units A to L and folders FL¹ to FL⁴, one for each group of three printing units. Each printing unit may be assumed to be designed to print eight pages, and each group of three printing units, and the folder therefor is provided with a double motor drive, although it is of course to be understood that the number of units in each group may be either decreased or increased as desired. 55

As illustrated the group of printing units A, B and C and folder FL¹ has a drive M¹ comprising a large motor 6 and a small motor 7, said motors driving through a chain 8 and sprockets 9 and 10, a counter shaft 11 which is connected to a shaft 14 by a set of gears G¹ 65 one of which is slidable on the shaft 11. The printing units A, B and C and folder FL¹ are each connected to shaft 14 by a set of bevel gears, one gear of each set being slidable on said shaft to disconnect its respective unit 70 therefrom. The remaining groups of printing units and folders are respectively provided with like motor drives M², M³ and M⁴ which drive through like connections shafts 15, 16 and 17 of said groups. Each motor 75 drive is preferably designed to be capable of driving as many as six printing units and one folder and the shafts 14, 15, 16 and 17 are provided with couplings therebetween and between sections thereof whereby the motors 80 may be so employed and moreover employed alternatively.

More specifically the shafts 14 and 15 have a coupling 18 therebetween while shafts 15 and 16 have a coupling 19 therebetween, and shafts 16 and 17 have a coupling 20 therebetween. Further the shaft 15 is interrupted between printing units D and E and has one of the gears G² rotatably mounted on one section thereof to be coupled to the two sections of said shaft selectively or to both by couplings 21 and 22. Similarly the shaft 16 is interrupted between printing units H and I and one of the gears G³ is mounted on one section and provided with couplings 23 and 24 to connect the same to the two sections of said shaft selectively, or to both. 95

The aforescribed driving connections provide a large number of driving combina- 100

tions for the units and the following tabulation sets forth certain of such combinations.

Comb.	Press	Drive	Folder	Couplings		Slip gears	
				In	Out	In	Out
10	1 ABC	M ¹	FL ¹	18	G ¹ -A		
	2 DEF	M ²	FL ²	18-19	G ²

	14 HIJKL	M ⁴	FL ¹	23-24-20	19	G ⁴	G ³
	15 ABCDEF	M ¹	FL ²	18-21-22	19	G ¹ -A	G ²
	16 ABCDEF	M ²	FL ²	18-21-22	19	G ² -A	G ¹
	17 GHJKL	M ³	FL ⁴	23-24-20	19	G ³ -G	G ⁴
	18 GHJKL	M ⁴	FL ¹	23-24-20	19	G ⁴ -G	G ³

20 As is apparent from the above tabulation the aforescribed driving connections enable the units to be operated as four sextuple presses each to print a 24 page paper; or three octuple presses each to print a 32 page paper; or two dessuple presses each to print a 40 page paper; or as two sextuple presses each to print a 48 page paper. Also, as is apparent from the following tabulation each of the aforementioned presses of four or 30 more units may be driven by either of a plurality of drives selectively.

As shown in Fig. 1 each of the couplings and each of the slip gears designated in the foregoing tabulation is provided with a switch arm having two sets of cooperating stationary contacts and as hereinafter set forth these switch arms and their cooperating contacts serve to control signal lamps for indicating whether or not the driving connections are properly set for a given drive combination.

Referring now to Fig. 2, the same shows the printing units, folders and drives together with control panels C¹, C², C³ and C⁴, one for each driving unit and folder, and switches 30 to 42, inclusive, for effecting control commutations in accordance with the aforescribed mechanical drive combinations. As will be understood, the control station of each printing unit and folder must be given control over the drive to which said unit or folder is coupled and as will be apparent from the aforescribed mechanical drive combinations certain of the stations must be capable of connection to any one of three drives. Also as will hereinafter appear other commutations are to be effected and the switches 30 to 42 provide for all such commutations and further provide for disconnection of the control station of each printing unit or folder when silenced.

Each of the switches 30 to 42, inclusive, has two positions to which it may be moved selectively, one position being indicated by the full line extending obliquely from the

right side thereof and the other position being indicated by the dotted oblique line. Each switch when positioned as indicated by the full line serves to connect the cable leading thereto from the left to the cable, if any, leading from the upper end thereof, while in the absence of the latter cable the switch disconnects the former cable from circuit. On the other hand, each switch when positioned as indicated by the dotted line connects the cable leading thereto from the left to the cable leading from its lower end. In the following description the full line position of the control switches will be termed the normal position thereof, while the dotted line position will be termed the parallel position thereof.

For a better understanding of the function and operation of the various control switches the control commutations effected by a plurality of switches as for example switches 35 and 36 will be described. Switch 35 in its normal position, connects the station S of press E to switch 36, and the latter switch in its normal position connects the former station to control panel C². On the other hand, by moving the switch 36 to its parallel position, the circuit from the aforementioned control station S may be shifted to panel C¹ and by moving the switch 35 to its parallel position the circuit from said station may be shifted to panel C². The other control switches effect similar control commutations and the following tabulation sets forth the required control commutations for the drive combinations set forth in the preceding tabulation.

Comb.	Press	Folder	Drive	Control switches	
				Parallel	Normal
1	ABC	1	M ¹	30-31-32-33-34	36
2	DEF	2	M ²	32-33-34-35	30-31

17	GHJKL	4	M ³	36-38-39-40	37-42
18	GHJKL	4	M ¹	38-42	37-39-40-41

As shown in Fig. 2, each control switch is provided with two sets of auxiliary stationary contacts to be respectively bridged in the normal and parallel positions of said switch, and as hereinafter set forth such contacts serve to control signalling lamps for indicating whether or not the control switches are properly set for a given drive combination.

Referring now to Figs. 3 and 4, the same diagrammatically illustrate two banks of

signal lamps SL^1 and SL^2 , the former bank to be controlled by the contacts associated with the aforescribed couplings and slip gears and the latter bank to be controlled by the auxiliary contacts associated with the aforescribed control switches. The lamps of each bank are arranged in 18 horizontal rows, one row being provided for each of the combinations set forth in the foregoing tabulations. Each horizontal row of lamps of the bank SL^1 is provided with a lamp corresponding to each coupling and slip gear, while each horizontal row of lamps of the bank SL^2 is provided with a lamp corresponding to each control switch. The lamps corresponding to each coupling and slip gear in bank SL^1 are arranged one above the other to provide vertical rows, and the lamps corresponding to each control switch in bank SL^2 are similarly arranged.

Each bank of lamps has a selector switch SS associated therewith comprising a movable contact arm and eighteen cooperating stationary contacts each corresponding to one drive or control commutation as the case may be. The supply circuit for each bank of lamps is indicated by lines L^1 — L^2 and the movable contact element of each of the switches SS is permanently connected to the line L^2 while the stationary contacts of said switches are each permanently connected to the lower terminals of all of the lamps corresponding to a given drive or control commutation as the case may be. The upper terminals of the lamps in the bank SL^1 are arranged to be selectively connected to line L^1 by the switches associated with the aforescribed couplings and slip gears while the upper terminals of the lamps in bank SL^2 are arranged to be selectively connected to line L^1 by the auxiliary switches associated with the aforescribed control switches.

To assist in understanding the circuit connections for the signal lamps in banks SL^1 and SL^2 the settings of the slip gears and couplings for the various drive combinations are shown opposite the corresponding rows of lamps in the bank SL^1 while the settings of the control switches for the various combinations are shown opposite the corresponding rows of lamps in bank SL^2 . Also in Fig. 3 the auxiliary contacts associated with the couplings and slip gears are diagrammatically illustrated above their corresponding vertical rows of lamps and it is assumed that in the engaged position of a coupling or slip gear its associated movable contact element engages the left hand stationary contacts, while in the disengaged position thereof its associated movable contact element engages the right hand stationary contacts. Also in Fig. 4 the auxiliary contacts associated with the control switches are shown directly above their corresponding vertical rows of lamps and it is assumed that in the parallel position

of a control switch its associated contact element engages the left hand stationary contacts, while in the normal position thereof the associated movable contact element engages the right hand stationary contacts. 70

It will be apparent upon examination of the circuit connections shown in Fig. 3 that upon setting of the selector switch SS^1 in a given position for a given drive combination all of the lamps in the row corresponding to such combination will be lighted, providing the slip gears and couplings are properly set for such drive combination. Also it will be apparent upon examination of the circuit connections in Fig. 4 that upon setting of the selector switch SS^2 in a given position for a given control combination, all of the lamps in the row corresponding to such combination will be lighted, providing the various control switches are properly set for such control combination. 80

For example, assuming that it is desired to set the drive connections and also the control switches for combination 7 in the foregoing tabulations, selector switches SS^1 and SS^2 90 are set in the dotted line positions indicated in Figs. 3 and 4 to connect all of the lamps in the rows corresponding to such combinations to line L^2 . In Fig. 3 it will be noted that for drive combination 7 it is necessary to set couplings 22 and 19 in their engaged positions; couplings 21 and 23 in their disengaged positions, and slip gears G^2 and G in their engaged positions. Assuming that said couplings and slip gears are set in this manner, the lamps corresponding to couplings 22 and 19 and the slip gears G^2 and G will then be lighted by connection thereof to line L^1 through the movable contacts and their left hand stationary contacts, while the lamps corresponding to couplings 21 and 23 will then be lighted by connection thereof to line L^1 through the associated movable contacts and their right hand cooperating stationary contacts. 100

It should also be noted that the other lamps in the row corresponding to drive combination 7 will be lighted through the medium of the switches associated with the aforesaid couplings and slip gears. The lamp corresponding to coupling 18 will be energized through the medium of the contacts associated with coupling 21; the lamps corresponding to couplings 20 and 24 will be energized through the medium of the contacts associated with coupling 23; the lamps associated with slip gears G^1 and G^3 will be energized through the medium of the contacts associated with slip gear G^2 and the lamps corresponding to slip gears G^4 and A will be energized through the medium of the contacts associated with slip gear G . 115

Also in Fig. 4, it will be observed that upon setting of the control switches in the required positions for combination 7 the lamps corresponding to switches 32, 35, 37, 38 and 41 will 120 130

be lighted by connection thereof to line L^1 through the medium of the movable contacts associated with said switches and their left hand cooperating stationary contacts, while 5 the lamps corresponding to control switches 33, 34 and 39 will be lighted by connection thereof to line L^1 through the medium of the movable contacts associated with said latter switches and their cooperating right hand 10 stationary contacts. The other lamps in the row corresponding to combination 7 will be lighted by connection to line L^1 through the medium of the contacts associated with the aforementioned control switches. The lamps 15 corresponding to control switches 30 and 31 will be energized through the medium of the contacts associated with switch 32; the lamp corresponding to control switch 36 will be energized through the medium of the auxiliary contacts associated with switch 37; the lamp corresponding to switch 40 will be energized through the medium of the contacts associated with switch 39 and the lamp corresponding to switch 42 will be energized 20 through the medium of the auxiliary contacts associated with transfer switch 41.

In connection with the foregoing it should be noted that although separate banks of signal lamps are employed for indicating the 30 setting of the drive connections and the control switches it is apparent that the two banks of lamps may be combined if desired and a single selector switch can be employed in connection therewith. Furthermore, it is apparent that where certain of the couplings, 35 slip gears or the control switches do not enter into a given drive combination the corresponding signal lamps may be omitted in the row corresponding to such combination.

40 What I claim as new and desire to secure by Letters Patent is:

1. In combination, a plurality of driven and motor driving units, devices to be set in different relative positions to provide at least 45 three different drive combinations between said units, a plurality of rows of signal lamps each corresponding to one of said drive combinations and containing a lamp corresponding to each of said devices, a selector switch 50 requiring setting in different positions for said drive combinations and means for energizing all of the lamps corresponding to a given drive combination upon proper setting of the devices and said selector switch for such combination.

2. In combination, a plurality of driven and motor driving units, devices to be set in different relative positions to provide at least 55 three different drive combinations between said units, a plurality of rows of signal lamps, each row corresponding to one of said drive combinations and containing a lamp corresponding to each of said devices, a selector switch associated with said lamps to be 60 set in different positions for said drive com-

bination, and circuit connections controlled by said devices and said selector switch for energizing all of the lamps in a given row upon proper setting of said devices for the drive combination corresponding to said row. 75

3. In combination, a plurality of driven and motor driving units, drive commutating means therebetween including releasable power transmitting devices to be set in different relative positions to provide at least 80 three different drive combinations, a controller for each of said driving units, a control station for each of said driven units, commutating means between said controllers and said stations including switches to be set in different relative positions to connect said controllers and said stations in different combinations corresponding to said drive combinations, a plurality of rows of lamps each corresponding to one of said drive combinations and control means for said lamps insuring energization of all of the lamps in a given row upon proper setting of said releasable power transmitting devices and said control switches for a given drive combination. 85

4. In combination, a plurality of driven units, a plurality of motor driving units, a plurality of devices adapted to be set in different positions to render certain of said motor units capable of driving different driven units to provide at least three different drive combinations, a plurality of rows of signal lamps, each row corresponding to one of said drive combinations and containing a lamp corresponding to each of said devices, and means for energizing all of the lamps in a given row upon proper setting of said devices for a corresponding drive combination. 95

5. In combination, a plurality of driven units, a plurality of motor driving units, a plurality of devices, certain of which are adapted to be set in different positions to render certain of said motor units capable of driving different driven units to provide at least three different drive combinations, a plurality of rows of signal lamps, each row corresponding to one of said drive combinations and containing a lamp corresponding to each of said devices, and circuit connections controlled by said devices for energizing all 105 of the lamps in a given row upon proper setting of said devices for the drive combination corresponding to said row. 110

In witness whereof, I have hereunto subscribed my name.

EDWIN W. SEEGER.
